United States Patent [19]

Gamm

[11] Patent Number: Des. 285,261

[45] Date of Patent:  Aug. 26, 1986

[54] PURSE POCKETED SHOE

[75] Inventor: Robert J. Gamm, St. Louis, Mo.

[73] Assignee: Kangaroos U.S.A., Inc., St. Louis, Mo.

[] Term: 14 Years

[21] Appl. No.: 498,492

[22] Filed: May 26, 1983

[52] U.S. Cl. D2/309

[58] Field of Search .... D2/309-313, D2/314, 315, 319; 36/132, 136, 83, 84, 113-115, 129, 50, 32 R
